UNITED STATES PATENT OFFICE.

HENRY E. VAN NESS, OF ELMIRA, NEW YORK, ASSIGNOR TO ECLIPSE MACHINE COMPANY, OF ELMIRA, NEW YORK, A CORPORATION OF NEW YORK.

ENGINE-STARTER.

1,255,362.

Specification of Letters Patent.

Patented Feb. 5, 1918.

Application filed May 16, 1917. Serial No. 168,952.

To all whom it may concern:

Be it known that I, HENRY E. VAN NESS, a citizen of the United States, residing at Elmira, in the county of Chemung and State of New York, have invented certain new and useful Improvements in Engine-Starters, of which the following is a specification.

My invention relates to an engine starter such as exemplified in patents heretofore issued to Vincent Bendix, for instance Patent No. 1,125,935, dated January 26, 1915, and Patent No. 1,172,864, dated February 22, 1916, which starter is characterized by a prime mover such as an electric motor and a transmission or drive for transmitting the power of such motor, by means of a rotatable screw shaft and a pinion mounted thereon, to a member of the engine to be started, such as the fly wheel. This particular drive comprises a screw shaft operated directly or indirectly by the motor and a pinion screw-threaded on the shaft and having longitudinal movement there-

with.

My invention pertains to means for preventing creeping movement of the pinion on the screw shaft due to vibration of the automobile on which such engine starters are commonly employed, such means being arranged to prevent any possible slight rotation of the pinion or shaft which might advance such pinion into contact with the fly wheel and thereby cause a clashing or rasping sound. The means constituting my invention are so designed as not to interfere in any manner with the ordinary or normal operation of the drive.

In the drawing Figure 1 is an elevation of a drive showing my invention incorporated therein; Fig. 2 a cross section on the line 2-2 of Fig. 1; and Fig. 3 a detail view.

The general construction of the drive is the same as shown in the patents aforesaid and it will therefore be sufficient to say that the same comprises in connection with the extended armature shaft 1 of an electric motor indicated at A, a rotatable hollow screw shaft 2, a pinion 3, screw-threaded upon the shaft and adapted to mesh with the teeth 4^a of the fly wheel 4, a coil spring 5 constituting the yielding driving connection between the collar 6 secured to the armature or driving shaft 1 by the pin or bolt 7, and a bolt or stud 8 which screws into the en-

largement 2^a of the screw shaft. The pinion 3 is shown in the drawings in its retracted or home position. When the armature shaft and consequently the screw shaft is rotated, this pinion is advanced automatically in a direction longitudinally of the screw shaft and into mesh with the fly wheel teeth. This longitudinal movement is stopped by the contact of the pinion against the stop-nut or collar 9 which is secured to the inner end of the screw shaft and adjacent the starting motor. At this time the pinion takes up the rotary movement of the screw shaft and drives the fly wheel. After the gas engine is started on its own power, the pinion is automatically moved to its home position shown.

The means provided for preventing the described creeping movement of the pinion consists of a light wire 10 constituting a spring and mounted in one of the threads 2^b of the screw shaft in such manner that it will project slightly beyond the face of such thread and impart a yielding resistance to the pinion when the groove in the internal bore thereof comes into contact therewith. In the present instance this spring is a short wire loosely retained at its ends within a slot 11 which runs longitudinally of such thread and which communicate with end holes or recesses 11^a into which the free ends of the spring 10 enter.

In case of any creeping movement of the pinion, such movement will be stopped when the pinion meets the yielding resistance offered by the spring, which resistance takes effect before the pinion has crept far enough to come into contact with the fly wheel. This resistance is rather slight but sufficient to stop the creeping movement and yet not sufficient to interfere with the positive longitudinal advancement of the pinion in the regular operation of the drive. It will be understood that the free ends of the spring or wire are held loosely in the holes in the thread, so that while the spring normally projects slightly above the surface of the thread it will be forced into the slot when the pinion is positively advanced, at which time the holes properly accommodate the ends of the springs in their endwise movements.

I claim:

1. In a drive of the character described, the combination of a threaded shaft, a

- pinion screw-threaded thereon for rotary movement therewith and longitudinal movement thereof, and means mounted on one of the threads of such shaft and coacting with the pinion to prevent creeping thereof.
2. In a drive of the character described, the combination of a threaded shaft, a pinion screw-threaded thereon for rotary movement therewith and longitudinal movement thereof, and means mounted on one of the threads of such shaft and coacting with the pinion to prevent creeping thereof, such means comprising a spring projecting slightly beyond the surface of such thread.
3. In a drive of the character described, the combination of a threaded shaft, a pinion screw-threaded thereon for rotary movement therewith and longitudinal movement thereof, and means mounted on one of the threads of such shaft and coacting with the pinion to prevent creeping thereof, such means comprising a spring in the form of a wire projecting slightly beyond the surface of such thread, and the said thread having a slot to receive such wire.
4. In a drive of the character described, the combination of a threaded shaft, a pinion screw-threaded thereon for rotary movement therewith and longitudinal movement thereof, and means mounted on one of

the threads of such shaft and coacting with the pinion to prevent creeping thereof, such means comprising a spring in the form of a wire projecting slightly beyond the surface of such thread, and said thread having holes 35 to loosely receive the free ends of the wire.

5. In a drive of the character described, the combination of a threaded shaft, a pinion screw-threaded thereon for rotary movement therewith and longitudinal movement thereof, and means mounted on one of the threads of such shaft and coacting with the pinion to prevent creeping thereof, such means comprising a spring in the form of a wire projecting slightly beyond the surface 40 of such thread, and said thread having a slot and holes at the ends of such slots to receive the wire.

6. In a drive of the character described, the combination of a threaded shaft, a pinion screw-threaded thereon for rotary movement therewith and longitudinal movement thereof, and means mounted on one of the threads of such shaft and coacting with the pinion to prevent creeping thereof, said 50 thread being located intermediate the threaded shaft to stop the said creeping movement in an early stage.

HENRY E. VAN NESS.
